(57)

CLAIM

The ornamental design for a macro base station, as shown and described.

DESCRIPTION

FIG. 1 is a perspective view of a macro base station; FIG. 2 is a front view of the macro base station; FIG. 3 is another perspective view of the macro base station; FIG. 4 is a back view of the macro base station; FIG. 5 is a top view of the macro base station; FIG. 6 is bottom view of the macro base station; FIG. 7 is a side view of the macro base station; and, FIG. 8 is another side view of the macro base station. The broken lines shown in the drawings illustrate portions of the macro base station that form no part of the claimed design.
